WALL LAMP

Linster D. Toler, Baltimore, Md., assignor to Benjamin Bleiberg and Harry E. Kahn, both of Baltimore, Md.

Application March 22, 1951, Serial No. 14,591

Term of patent 14 years

(Cl. D48—4)

To all whom it may concern:

Be it known that I, Linster D. Toler, a citizen of the United States, residing in Baltimore, State of Maryland, have invented a new, original, and ornamental Design for a Wall Lamp, of which the following is a specification, reference being had to the accompanying drawing, forming a part hereof.

The back of the device is unornamented.

I claim:

The ornamental design for a wall lamp, as shown and described.

LINSTER D. TOLER.
